CLAIM

I claim the ornamental design for a wine aerator, as shown and described.

DESCRIPTION

FIG. 1 is a perspective view of a wine aerator;

FIG. 2 is a top view thereof;

FIG. 3 is a bottom plan view thereof; and,

FIG. 4 is a side view thereof.

1 Claim, 2 Drawing Sheets

FIG.1.

FIG.2.

FIG. 3.

FIG. 4.
